CLAIM

(63) Continuation of application No. 29/313,952, filed on
Feb. 20, 2009, now Pat. No. Des. 612,001.

The ornamental design for a sports goal, as shown and
described.

(51) **LOC (9) Cl.** **21-02**

DESCRIPTION

(52) **U.S. Cl.** **D21/699**

FIG. 1 is a front elevation view showing a first embodiment of
my new design for a sports goal;

(58) **Field of Classification Search** **D21/302,**

FIG. 2 is a rear elevation view of the embodiment of the sports
goal shown in FIG. 1;

D21/303, 305, 699, 701-705, 473/415, 416,

FIG. 3 is a left side elevation view of the embodiment of the
sports goal shown in FIG. 1;

473/421, 431-435, 439, 446-448, 454-456,

FIG. 4 is a right side elevation view of the embodiment of the
sports goal shown in FIG. 1;

473/470-472, 476-789; 273/317-317.3,

FIG. 5 is a top plan view of the embodiment of the sports goal
shown in FIG. 1;

273/348, 382, 389, 394, 398, 400, 402-404,

FIG. 6 is a bottom plan view of the embodiment of the sports
goal shown in FIG. 1;

273/407, 408, 410

FIG. 7 is a front perspective view of the embodiment of the
sports goal shown in FIG. 1;

See application file for complete search history.

FIG. 8 is a bottom perspective view of the embodiment of the
sports goal shown in FIG. 1;

(56) **References Cited**

FIG. 9 is a front elevation view showing a second embodiment
of my new design for a sports goal;
